UNITED STATES PATENT OFFICE.

GEORGE LAWSON BALLARD, OF NORRISTOWN, PENNSYLVANIA, ASSIGNOR TO WILD-
MAN MFG. CO., OF NORRISTOWN, PENNSYLVANIA, A CORPORATION OF PENNSYL-
VANIA.

DOG FORM OF CIRCULAR-KNITTING MACHINES.

1,253,563.

Specification of Letters Patent. Patented Jan. 15, 1918.

Application filed March 20, 1916. Serial No. 85,473.

To all whom it may concern:

Be it known that I, GEORGE LAWSON BAL-
LARD, a subject of the King of Great Britain,
residing at Norristown, Pennsylvania, have
invented certain new and useful Improve-
ments in Dog Forms of Circular-Knitting
Machines, of which the following is a speci-
fication.

In circular knitting machines having a
needle cylinder and needle dial with dogs
on the cylinder, engaging dogs on the dial
for holding these parts in fixed relation to
each other, the fabric must be drawn down
by the take up mechanism between the mem-
bers of each pair of dogs, and against the
resistance arising from the presence of the
dogs thereon. Ordinarily in such machines
the dial post and dial and dial cam are all sup-
ported by a yoke connected with the cam ring
or carrier belonging to the needle cylinder
and in case of wear of the cam carrier or its
bearing in the fixed frame, in that type of
machine in which the cam carrier rotates,
the irregular movement or wabbling of the
cam carrier due to this looseness will dis-
place the needle dial in relation to the nee-
dle cylinder, so that in machines adapted to
make fine gage work not only will the regu-
lar and even formation of the loops be
affected adversely but the irregular or wab-
bling movements of the dial in relation to
the cylinder will cause the dogs of the dial
to move or reciprocate in relation to the
cylinder dogs, thus subjecting the fabric to
an undesirable rubbing action. Furthermore
with a worn cam ring or bearing or
one having considerable lateral play in its
bearings in the fixed frame, there will result
a displacement of the dial in relation to the
cylinder when welts are being forced through
between the dogs, the pressure being com-
municated directly by the welt or extra
thickness to the dial dogs and thence to
the dial, the latter being free to be dis-
placed because it is supported by the cam
ring which, as stated, may fit loosely in its
bearing, due to wear.

My improvement consists, in a dog form
of rib knitting machine, of means for hold-
ing the dial against irregular or wabbling
movements, said means preventing displace-
ment of the dial in relation to the needle
cylinder and preventing undesirable move-
ment of the dial dogs in relation to the cyl-
inder dogs.

In the drawings,

Figure 1 is a sectional view with parts in
elevation of one form of the machine.

Fig. 2 is a plan view of the dial cam car-
rier with the connection for turning it. 68

Fig. 3 is a view similar to Fig. 1 of an-
other form of the machine.

In Figs. 1 and 2 the needle cylinder 1 is
shown as fixed by screws, as at 1^a, to the
fixed base or frame 1^a. The needle dial is 65
shown at 2, the dial cam carrier at 3 and the
cylinder cam carrier at 4. The dogs be-
tween the cylinder and dial are indicated
at a, b, these being of substantially ordinary
form, one, a, being fixed to the needle cyl-
inder and the other to the dial. It will be
understood, however, that various forms of
dogs may be used and these may be of the
vibrating type adapted to open and close
serially to permit the fabric at times to pass 70
freely between them. Whatever form of
dogs may be used, it is important for the
best effect that they be not affected by any
irregular or wabbling movement of the dial,
and on the other hand the holding means 80
for the dial should be such that the dial itself
will not be affected in its relation to the nee-
dle cylinder by any undue pressure brought
to bear by the fabric upon the dial dogs.

In carrying out the invention, therefore, 85
I employ a fixed support or ring 13 above
the dial, this being held rigidly on the fixed
frame 1^a by a plurality of standards 14.
Mounted in connection with and sustained
by this fixed support 13 is a member 6. 90
This is held by the support 13 against dis-
placement both vertically and laterally. It
rests upon a ledge or ring 34 secured to the
fixed support 13, and it has a running fit
with the said fixed support and the latter 95
partly overhangs the rotary member, and
affords the upper bearing therefor.

This rotary member 6 may assume vari-
ous forms but in the particular construction
illustrated, it is in the form of a ring or 100
plate. It is open for the passage of the
yarn or yarns, one opening being shown
at 6^a.

The dial post 7 is supported by this ro-
tary member, said post extending up through 105
an opening arranged centrally thereof, and
having its upper screw threaded end receiv-
ing a nut 7^a by which the post may be ad-
justed vertically.

The nut simply rests upon the upper face 110

of the ring and it is fixed in adjusted position by a set screw 7^b.

The dial is attached to the lower end of the post by a screw 2', passing through a boss on the bottom of the dial into the post, and, as above stated, the dial post, together with the dial, is held against movement relative to the needle cylinder by dogs arranged between these parts.

- 10 For driving the dial cam carrier 3 and the rotary member 6 in unison to respectively operate the dial and needles and feed the yarn, various means may be employed, but in the particular construction, shown 15 in Fig. 1, a link 8 is connected with the dial cam carrier or cap 3 by a screw 35. This is located near the outer edge of the said dial cap and the link extends in a direction substantially tangential to an arc 20 struck from the center of the dial post, the outer end of said link 8 being screw-threaded and receiving nuts 37, by which a clamp 36 carrying said link may be fixed to the post 5, secured to the cylinder cam ring. 25 This connection is such that any irregular movement of the cylinder cam ring will not exert lateral or other pressure on the dial cam carrier, and consequently there will be no tendency to force the dial post 30 with its dial out of proper axial relation with respect to the cylinder and oscillation of the dial will be prevented, as well as movement of one dog on the other. Any irregularity in the movement of the cylinder 35 cam will be compensated for by the tangential disposition of the link 8, which instead of forcing the dial cap and post laterally will simply cause a slight change in a circumferential direction in the position of the 40 dial cap.

The connection to the plate 6 may assume various forms, but in the particular construction, shown in Fig. 3, it consists of a bar or post *c* screwed into the dial cam cap 45 or carrier and having its upper end entering an opening in the rotary member 6, so that this member will move in unison with the dial cam carrier.

It will now be observed that the connection 50 for driving the dial cam or cap, being of a character to compensate for irregularities in the movement of the cylinder cam to prevent lateral strain on the dial support or post, and said support being sustained

55 by the member 6 in connection with the fixed frame against tipping, wabbling, and against vertical or lateral displacement, the dial will be held in true relation to the needle cylinder and there will be no undue 60 movement of the dial dog in relation to the

cylinder dog, which would arise were the dial subjected to the irregular movements of the needle cylinder cam.

Instead of fixing the dial to the dial post, under which condition the dial post is held 65 against rotation, I may allow the dial post to rotate, as shown in Fig. 3, and simply hold the dial in position by its dog. In this construction the dial post is keyed at 7^x to the rotating plate 6, and the dial is supported by resting upon a collar 7^b on the post, said collar being secured thereto by the screw 7^c, shown in Fig. 2.

For driving the rotary plate 6 in unison with the dial cam carrier or cap 3, the post 75 above described may be used, connecting the dial cam carrier with said plate, or, as shown at 9, an arm connected rigidly with the hub of the plate 6 loosely engages the pin 9^a on the post 5, the arm being forked 80 to receive the pin, this connection being in the nature of a compensating one to prevent any irregularities in the movement of the cylinder cam from placing undue strain on the dial post or plate 6.

It will be understood that this arm 9 may be used in Fig. 3 in place of the post there shown to make the ring 6 run in unison with the dial cam.

I claim:—
In combination in a circular rib knitting machine, a needle cylinder, a needle dial, a dial post, cylinder and dial cams, cylinder and dial dogs between the cylinder and dial and between which dogs the fabric must pass, said dogs holding the dial against circumferential displacement in relation to the cylinder, means for supporting the dial post and dial independently of the cylinder cam against vertical or lateral displacement in 95 relation to the cylinder to thereby maintain the dogs in prescribed relation to each other, said means comprising a rigid overhead frame member and a rotary member supported thereby against displacement vertically or laterally and open for the passage of the yarn, and compensating means for driving the dial cam and said rotary member from the cylinder cam, said driving means comprising a connection from the cylinder 100 cam to one of said parts and a post extending between and rigidly connecting said rotary member and the dial cam, substantially as described.

In testimony whereof, I affix my signature.

GEORGE LAWSON BALLARD.
